γ -TRINITROBUTYRAMIDE

Robert H. Saunders, West Chester, Pa., assignor, by
mesne assignments, to the United States of America
as represented by the Secretary of the Navy
No Drawing. Filed Feb. 28, 1952, Ser. No. 274,071

1 Claim. (Cl. 260—561)

This invention relates to a new explosive compound, γ -trinitrobutyramide.

The new compound of the invention is a white crystalline substance which is stable at room temperature. It has properties making its use as an explosive highly feasible, having an oxygen balance within permissible limits and an impact sensitivity in the range of that of tetryl.

The new compound may be prepared by the addition of nitroform across the double bond of acrylamide. The reaction is carried out by adding a slight excess of nitroform to acrylamide and heating at about 55° centigrade for a short time. The product formed is then recovered through crystallization by strong cooling with a Dry Ice bath.

It is an object of the invention to provide a new explosive compound, γ -trinitrobutyramide.

The invention is illustrated by the following example, but it is not limited thereto:

Example.—To 142 milligrams of acrylamide was added a slight excess of nitroform in 2 milliliters of methanol.

2

The mixture formed was heated at 55° C. for about 20 minutes. The resulting mixture was diluted with 3 milliliters of water and the product recovered by crystallization accomplished by strong cooling in a dry ice bath.

5 The percentage composition calculated for $C_4H_6N_3O_7$ is, 21.6 percent carbon, 2.7 percent hydrogen, 25.2 percent nitrogen and the remainder oxygen. Analysis of the compound gave, 21.7 percent carbon, 2.8 percent hydrogen and 24.4 percent nitrogen. It has an oxygen balance of —29. Its melting point is 92° C. The compound has an impact sensitivity of 56 as determined with the Bureau of Mines impact machine, this figure being the distance in centimeters a 2 kilogram weight was required to fall in order to produce 50% shots. Its ignition time at a temperature of 220° centigrade was found to be 2 seconds. This is the time required to produce ignition of approximately 25 milligrams of compound contained in a 0.30 caliber cap shell when immersed in a Wood's metal bath at 220° C. The compound gave a 10 time of 5 minutes at 82.2° C. with the potassium iodide-starch stability test.

15 It is thus seen from the above that there has been provided a new compound having properties making its utility as an explosive highly feasible.

20 25 What is claimed is:
 γ -Trinitrobutyramide.
